UNITED STATES PATENT OFFICE.

HOWARD B. EYNON, OF LAKewood, OHIO, ASSIGNOR TO NATIONAL CARBON COMPANY, INC., A CORPORATION OF NEW YORK.

ARC-LAMP ELECTRODE.

Application filed June 11, 1919. Serial No. 303,302.

To all whom it may concern:

Be it known that I, HOWARD B. EYNON, a citizen of the United States, residing at Lakewood, in the county of Cuyahoga and 5 State of Ohio, have invented a certain new and useful Improvement in Arc-Lamp Electrodes, of which the following is a full, clear, and exact description.

This invention relates to an improvement 10 in arc lamp electrodes, and particularly to negative electrodes especially adapted for use in projection apparatus.

One of the most important requirements 15 which must be fulfilled for this type of service is arc steadiness, and my invention relates to, and especially discusses an electrode structure which satisfies this particular requirement.

I have found that the arc has a very 20 strong tendency to spring from the hottest part of a negative electrode and to remain there. I have found this to be especially true in the case of pure carbon electrodes or with electrodes in which no flaming ingredient 25 is present in close proximity to the portion of the electrode from which the arc springs. Although the same is true to a limited extent, of electrodes containing small amounts of flaming material, the 30 presence of flaming material is undesirable because it reduces the temperature of the arc stream and the intrinsic brilliancy.

In the single figure of the drawing I have 35 shown a method of accomplishing the desired result by means of an electrode having a central pin.

The structure shown in the drawing consists of an outer shell 3 of pure carbon, a central core 4 of graphite or graphitic material 40 and an intermediate filling 5 of powdered graphite or graphitic material held together by a small amount of a carbonaceous binder. The core, which preferably is forced or molded and then baked, is pushed 45 into a green or unbaked shell filled with the viscous filling of graphitic material and binder. The diameter of the hole in the shell is preferably twice that of the core pin, or greater. I have found that the core 50 is readily centered in the shell if the filling material consists of a mixture of fine graphite particles with a suitable quantity

of coarse particles. The coarse particles serve to properly center the pin in the shell and conduct the current to the core. During 55 burning the arc tends to remain on the graphite core because the shell and filling burn away more rapidly than the more resistant graphite core, thus permitting it to project from the shell. On account of its 60 central location and because it projects from the body of the electrode, the arc more readily springs therefrom. The filling material burns away more rapidly than either the shell or core, producing a groove 6 65 around the core. This tends to prevent the heat from radiating from the core to the shell and keeps the core at a high temperature. The shell of the electrode may be provided with a copper coating 7 and nickel 70 coating 8, as described in the patent to Perris, No. 1,241,270, dated Sept. 25, 1917.

Although I have set forth what I believe 75 is a reasonable explanation of the steadiness of the electrodes, it must be understood that my invention is not necessarily limited thereto.

Having described my invention, what I claim is:—

1. A negative projector electrode consisting of a carbon shell, a graphite core spaced therefrom and an intermediate filling of powdered graphite held together by a carbonaceous binder. 80

2. A negative projector electrode consisting of a carbon shell, a formed graphite core spaced therefrom and an intermediate filling of powdered graphite held together by a coked carbonaceous binder. 85

3. A negative projector electrode consisting of a carbon shell, a formed graphite core spaced therefrom, and an intermediate filling of powdered graphite, said filler containing a quantity of large graphitic particles adapted to space the core from the shell. 90

4. A negative projector electrode consisting of a carbon shell, a formed graphite core spaced therefrom and an intermediate filling of powdered graphite held together by a coked carbonaceous binder, said filler being in a more porous condition than the shell or core. 100

5. A negative projector electrode consisting

ing of a carbon shell, a carbonaceous core spaced therefrom, and an intermediate filling of powdered carbonaceous matter, said filler containing a quantity of large conducting particles adapted to space the core from the shell.

6. A negative projector electrode consists

ing of a carbon shell, a carbonaceous pin spaced therefrom, and an intermediate filling of powdered graphite held together by 10 a carbonaceous binder.

In testimony whereof, I hereunto affix my signature.

HOWARD B. EYNON.
